(57) **CLAIM**

The ornamental design for a pyramid child-proof bottle, as shown and described.

DESCRIPTION

FIG. 1 is a top front perspective view of a pyramid child-proof bottle, showing my new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken line portions of FIG. 7 are included to show unclaimed subject matter only and form no part of the claimed design.

1 Claim, 7 Drawing Sheets

FIG.1

FIG.2

FIG.3

FIG.4

FIG.5

FIG.6
